Primary Examiner — Derrick Holland*Assistant Examiner* — Jennifer O King(74) *Attorney, Agent, or Firm* — Evan Law Group LLC(57) **CLAIM**

The ornamental design for a flexible fuel generator, as shown and described.

DESCRIPTION

FIG. 1 is a front view of a flexible fuel generator;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front perspective thereof; and,

FIG. 8 is a back perspective view thereof.

The broken lines shown represent unclaimed subject matter and form no part of the claimed design.
